FOOD PACKAGING TRAY

Roy W. Bloch, Northbrook, and Donald K. Jewell,
Chicago, Ill., assignors to Ekco Products, Inc.,
Wheeling, Ill., a corporation of Illinois

Filed Aug. 20, 1968, Ser. No. 13,196

Term of patent 14 years

Int. Cl. D9—04

U.S. Cl. D9—219

FIG. 1

FIG. 2

FIG. 3

FIG. 4

FIG. 1 is a top plan view of a food packaging tray showing our new design.

FIG. 2 is a side elevational view thereof, the side opposite being identical thereto;

FIG. 3 is an end elevational view thereof, the end opposite being identical thereto.

FIG. 4 is a section taken along line 4—4 of FIG. 1.

We claim:

The ornamental design for a food packaging tray, substantially as shown and described.
